UNITED STATES PATENT OFFICE.

PETER STAREK, OF CHROME, NEW JERSEY.

COMBINED SHADE-HOLDER AND POLE.

1,135,331.

Specification of Letters Patent. Patented Apr. 13, 1915.

Application filed March 26, 1914. Serial No. 827,341.

To all whom it may concern:

Be it known that I, PETER STAREK, a subject of the Emperor of Austria-Hungary, residing at Chrome, in the county of Middlesex and State of New Jersey, have invented certain new and useful Improvements in Combined Shade-Holders and Curtain-Poles, of which the following is a specification.

10 This invention relates to certain new and useful improvements in combined shade holder and curtain pole.

The primary object of this invention is to provide a curtain pole for a window 15 adapted for incasing a complete shade roller structure and thereby protecting the same from dust and providing a dust-proof case for the entire rolled up portion of the shade at all times.

20 A further object is to provide a curtain pole consisting of hinged sections and having the curtain mounted upon one section thereof while the shade roller is journaled within the pole, the other section of which 25 is adapted as a dust-proof cover for inclosing the rolled up portion of the shade.

A still further object is to provide a dust- 30 proof casing for a shade and in which the shade roller is removable while the curtain 35 may be supported by the pole in the usual manner.

With these general objects in view and others that will appear as the nature of the invention is better understood, the same 35 consists in the novel combination and arrangement of parts hereinafter fully described, illustrated in the accompanying drawings, and pointed out in the appended claim.

40 In the drawings forming a part of this application and in which like designating characters refer to corresponding parts throughout the several views:—Figure 1 is an end elevation of the improved device 45 illustrated as mounted upon a window and having a shade and a curtain supported thereby. Fig. 2 is a perspective view of one end portion of the curtain pole with the cover section in its open position. Fig. 3 50 is a vertical transverse sectional view through the device showing the shade as partially unrolled. Fig. 4 is a similar view with the shade completely incased within the pole, the hinged section being shown in 55 dotted lines in its open position, and, Fig. 5 is an elevation view looking into the pole

of the end opposite to that shown in Fig. 2, the cover section being open.

Referring more in detail to the drawings, the window casing 10 is disclosed provided 60 adjacent the top thereof with opposite brackets 11 for mounting thereon horizontally the supporting pole 12. The pole consists of ornamental end knobs 13 to which one section 14 of the pole is permanently 65 secured by means of suitable hold-fast devices 15 extending through said section and into the reduced inner ends 16 of said knobs and whereby the section 14 which is semi-circular in cross-section is supported as 70 shown in Figs. 3 and 4 and thereby constituting the rear wall of a two-part tubular pole, a front section 17 of which is mounted thereon by hinges 18 arranged at the top of the pole and connecting the two semi-tubular sections together. One end of the pole is provided in the reduced knob portion 16 with a perforation or socket 19 as shown in Fig. 2 while the opposite knob portion carries the plate 20 with a T-shaped slot 21 and 80 whereby a shade roller 22 of the usual construction is adapted to be mounted between said end knobs and within the curtain pole by an engagement of the usual projecting end members of the roller with said socket 85 and slot. With the shade roller mounted within the tubular curtain pole, the shade 23 is adapted to move outwardly and inwardly of the hollow pole through the longitudinal side slot 24 formed therein by 90 means of co-operating cut-away portions 25 in the adjacent contacting edges of the two-pole sections while the window curtain 26 is secured to the movable hinge section 17, preferably at a point adjacent the top thereof as at 27, as illustrated in Figs. 3 and 4. 95

From this detailed description of the invention, it will be readily apparent that with the shade 23 adapted to be rolled and unrolled upon the roller 22 within the pole, 100 such operations are freely accomplished while the pole sections are in closed position, and by a slight movement of the hinge section 17 upon its hinges, the shade may be entirely received within the pole including 105 the bottom end weighting strip 26 as shown in Fig. 4, and whereby the complete shade is protected within the pole while at all times there is no liability of contact between the shade and the curtain at any 110 points adjacent to the supporting means therefor.

2
While the forms of the invention herein shown and described are what are believed to be preferable embodiments thereof, it is nevertheless to be understood that various forms and modifications thereof may be had without departing from the spirit and scope of the invention as claimed.

What is claimed as new is:—

10 In a device of the kind described, a shade roller support and guard comprising spaced end knobs, one of said knobs being provided at its inner end with an axial recess, the other of said knobs being provided at its inner end with a T-shaped slot extending 15 radially therein, said recess and slot being adapted to removably receive the pintles of

a shade roller, a semi-cylindrical pole section connecting said end knobs, and a second semi-cylindrical pole section hinged to one longitudinal edge of the first pole section and arranged when closed to cover the lateral opening of the T-shaped slot and having its free edge spaced from the remaining longitudinal edge of the first pole section when closed thereon to provide a 20 25 shade opening.

In testimony whereof I affix my signature in presence of two witnesses.

PETER STAREK.
